DESIGN FOR A PERFUME BOTTLE OR THE LIKE

Abraham Levy, New York, N. Y.

Application March 14, 1945, Serial No. 118,482

Term of patent 7 years

(Cl. D58—6)

To all whom it may concern:

Be it known that I, Abraham Levy, a citizen of the United States and a resident of the city, county, and State of New York, have invented a new, original, and ornamental Design for Perfume Bottle or the like, of which the following is a specification, reference being had to the accompanying drawing, forming part thereof, in which:

Fig. 1 is a front elevation of a perfume bottle showing my new design.

Fig. 2 is a side elevation of the same.

Fig. 3 is a rear view of the same.

I claim:

The ornamental design for a perfume bottle or the like, as shown.

ABRAHAM LEVY.
